CLAIM

The ornamental design for a sports pad for eyewear frames, as shown and described.

DESCRIPTION

FIG. 1 is a front elevational view of a sports pad showing my

design;

FIG. 2 is a rear elevational view of the sports pad shown in FIG. 1;

FIG. 3 is a front elevational view of a sports pad showing my new design in combination with a sports eyewear frame; FIG. 4 is a rear elevational view of the sports pad and sports eyewear frame shown in FIG. 3;

FIG. 5 is a right end elevational view of the sports pad and sports eyewear frame shown in FIGS. 3 and 4;

FIG. 6 is a left end elevational view of the sports pad and sports eyewear frame shown in FIGS. 3-5;

FIG. 7 is a top plan view of the sports pad and sports eyewear frame shown in FIGS. 3-6;

FIG. 8 is a bottom plan view of the sports pad and sports eyewear frame shown in FIGS. 3-7;

FIG. 9 is a front perspective view of the sports pad of my design in its normal, unstretched state prior to being stretched over the sports eyewear frame as shown in FIGS. 3-8;

FIG. 10 is a front elevational view of the sports pad shown in FIG. 9 in its normal unstretched state prior to being stretched over the sports eyewear frames as shown in FIGS. 3-8;

FIG. 11 is a rear elevational view of the sports pad shown in FIGS. 9 and 10 in its normal unstretched state prior to being stretched over the sports eyewear frames as shown in FIGS. 3-8;

FIG. 12 is a right end elevational view of the sports pad shown in FIGS. 9-11 in its normal unstretched state prior to being stretched over the eyewear frames as shown in FIGS. 3-8;

FIG. 13 is a top plan view of the sports pad shown in FIGS. 9-12 in its normal unstretched state prior to being stretched over the eyewear frames shown in FIGS. 3-8; and,

FIG. 14 is a bottom plan view of the sports pad shown in FIGS. 9-11 in its normal unstretched state prior to being stretched over the sports eyewear frames as shown in FIGS. 3-8.

The broken line showing of the frame in FIGS. 3-8 is for illustrative purposes only and forms no part of the claimed design and the omission of the side elements in FIGS. 9-14 is for ease of illustration only.
